STRAIGHTENING MACHINE

Benjamin P. Hazeltine, Wheeling, W. Va.

Application September 26, 1938, Serial No. 231,662

17 Claims. (Cl. 153—54)

This invention relates to the straightening of cylindrical blanks such as tubing, rods and like articles of circular cross section, and more especially to a method and apparatus in which blanks are straightened by the flights of rotating screws. The invention is particularly applicable to hot straightening such blanks, and is an improvement upon the invention disclosed in my Patent No. 1,758,699.

It is among the objects of this invention to provide a straightening method and apparatus, of the general character disclosed in my above-mentioned patent, in which the blank is moved axially as it is being rolled sideways, in which the direction of axial movement is periodically reversed, and in which all of the straightened blanks are moved axially in the same direction to the same predetermined point immediately before leaving the straightening apparatus.

In accordance with this invention a plurality of blank-straightening screw flights are rotatably mounted in a substantially horizontal parallel series and are adapted when a blank is laid transversely thereof to engage it on opposite sides at longitudinally spaced points, thereby providing a series of three point contacts. Some of these screws have right-hand flights, and the rest have left-hand flights, these right and left-hand screws being driven in a common direction of thread travel and preferably being disposed in alternating relation. The two groups of screw flights are adapted to periodically move vertically relative to each other so that the blank-engaging portions of one group are first above and then below the blank-engaging portions of the other group. Consequently, only one group of screws engages a blank at a time. The engagement of the blank on opposite sides by the screws creates a forward thrust, due to the rear threads, which is opposed by the reaction of the forward threads, and because the blank is supported at a plurality of longitudinally spaced points its behavior corresponds to that of a continuous beam. Also, its engagement on opposite sides by revolving screw threads causes the blank to rotate while moving in the direction of thread travel, so that the thrust acting upon longitudinally spaced points along the blank is applied progressively to its periphery. A straight blank moving through the threads will be subjected to no bending stresses, because the thrust will be uniform at each point of support. In the case of a bent or kinked blank, however, there will be created unevenly distributed stresses, due to the tendency for the points of support to be

out of line, and as the blank rotates the increased stresses applied to the bent portions act around the blank to bring it into line.

Due to the fact that only one group of screws engages the blank at a time, the blank is moved axially as it is carried sideways by the screws. By periodically moving the other group of screws into engagement with the blank and simultaneously removing it from engagement with the first group, its direction of axial movement is reversed. As a result, every point along the periphery of the blank is sooner or later subjected to straightening forces. Means is associated with the delivery ends of the screws of one group for raising the blank clear of the other group of screws to thereby feed it axially in only one direction. After this axial movement of the blank has been arrested by a stop, the blank rolls onto a delivery table or conveyor.

The invention is illustrated in the accompanying drawings in which Fig. 1 is a plan view of a preferred embodiment of apparatus for practicing my invention; Fig. 2 is a side view thereof; Fig. 3 is a fragmentary view of the right end of the apparatus; Fig. 4 is an enlarged end view taken on the line IV—IV of Fig. 1; and Fig. 5 is a diagrammatic view of a modification of this invention.

Referring to the drawings, a plurality of screw flights 1 are journaled in bearings 2 mounted on horizontally spaced parallel channels 3 which form a stationary framework. The threads or flights are square and of relatively large diameter, although other styles of thread may be used. All of the screws mounted on this frame have threads extending in the same direction; that is, they are all either right or left-hand screws. These screws are all driven in the same direction by a common shaft 6 through bevel gears 7 and 8 mounted on the shaft and screws. The screws are adapted to receive between the turns of their flights a cylindrical blank 9 placed transversely of the screws. Any suitable blank feeding device, not shown, may be used for delivering cylindrical blanks to the screws, and likewise any suitable receiving apparatus may be mounted at the delivery ends of the screws to catch the blanks as they are delivered therefrom.

A plurality of similar screws 11, having flights wound in the direction opposite to those of screws 1, are mounted between the latter preferably in alternating relation therewith. These screws are likewise adapted to receive a blank between their flights; however, it is a feature of this invention

that these screws are mounted on a vertically movable frame so that they can be raised and lowered to periodically lift a blank from the other screws and return it thereto. Accordingly, this 5 second frame comprises a pair of horizontally spaced parallel channels 12 mounted between fixed channels 3 and rigidly connected together by transverse beams 13 (Fig. 4). These channels carry bearings 14 in which screws 11 are journaled. The ends of the screws are provided with spur gears 16 which mesh with similar gears 17 on the intermediate screws, whereby the two groups of screws are rotated in opposite directions but their thread travel is in the same direction. 10 As shown in Fig. 4, the inner or vertically movable frame is supported by means of depending bars 18 connected to its cross beams 13 with their lower ends pivoted in the laterally projecting arms of bifurcated bell cranks 19. These cranks are 15 rigidly mounted on horizontally spaced shafts 21 and 22 journaled in bearings 23 mounted on suitable stationary supports. The end cranks of the two shafts are connected together by links 24 pivotally mounted in the lower arms of the 20 cranks. Extending laterally from shaft 22 is an arm 26, the outer end of which is mounted on the top of the vertically movable piston rod 21 of a suitable fluid pressure cylinder 28. When the piston is raised in the cylinder it raises this arm 25 and thereby turns the shafts which swing the lateral arms of their bell cranks upwardly and thereby lift the movable frame. To aid the piston in this operation the frame is nearly balanced by means of counterweights 29 mounted on horizontal bars 31 carried by the inner ends of arms 30 32 projecting inwardly from shaft 22.

In the lower or inoperative position of the movable frame, as shown in the drawings, the axes of screws 11 carried by it are below the axes of screws 1 mounted on the fixed frame, but in 40 the upper position of the movable frame the axes of its screws are above the axes of the screws of the other group. However, for the purpose of this invention, this movement of the frame need 45 be but very little because all that is necessary is for the threads of one group of screws to lift the blank out of frictional engagement with the threads of the other group. The blank does not need to be lifted above the threads. Such movement of the inner frame does not unmesh spur gears 16 and 17 on the ends of the screws. On the contrary, the lifting of screws 11 causes their gears 16 to be turned slightly by gears 17, whereby the flights of screws 11 are turned backwardly a 50 very short distance which substantially compensates for the bodily longitudinal forward movement of the screws caused by cranks 19 swinging the movable frame transversely as they raise it.

60 In the use of this apparatus blank 9, delivered transversely of the screws, is engaged on opposite sides at longitudinally spaced points by adjacent threads of each screw of either the right or the left-hand group, depending on which group is uppermost at the time. With the screws rotating, the blank is rotated and simultaneously rolled or carried sideways, and the resultant thrust progressively applied to the periphery of the blank straightens it in the manner previously explained.

65 As all of the screws in each group have flights wound in the same direction, the blank is moved axially by either group while being carried sideways. The result is that the bending forces exerted on it in order to straighten it are applied progressively to its periphery throughout its 70

length. It is to permit this axial movement to take place continuously within a machine of reasonable size that the vertically movable group of screws is provided. That is, the blank is alternately engaged by each group of 5 screws, and, due to their flights being wound in opposite directions, the blank is first carried axially in one direction and then in the other.

To cause periodic raising and lowering of the movable frame for this purpose, pressure fluid 10 is supplied to and exhausted from cylinder 28 by suitable means (not shown) controlled by the axial movements of the blanks themselves. This control is preferably effected through the medium of electric flag switches mounted at both ends of 15 the machine in the path of the axially moving blanks. A suitable switch of this character comprises a plate 36 extending transversely of the machine at each end where it is supported for pivotal movement on a horizontal axis by means 20 of rigid upright members 37 mounted on top of the ends of fixed channels 3. Each plate carries on its outer face an electric contact member 38 adapted to engage a similar contact member 39 mounted on an arm 41 projecting laterally from 25 one of the uprights 37. One pair of contacts are brought together whenever an axially moving blank strikes one of the plate 36 any place along its length and swings it outwardly. The flag switch at the right of Fig. 1 is connected by a suitable 30 electric circuit to the fluid supply means, and the other is connected to the fluid exhausting means, whereby when a blank closes the right-hand switch fluid is supplied to cylinder 28 and the movable frame is lifted to cause its screws to 35 lift the blanks from screws 1 and carry them toward the opposite end of the machine. When one of the blanks strikes the left-hand plate 36, cylinder 28 is exhausted and the weight of the 40 movable frame causes it to fall and return the 45 blanks to screws 1 which again reverse the direction of their axial travel.

Another feature of this invention is that all of the blanks are delivered from the straightening machine at the same point longitudinally there- 45 of so that they can be trimmed to the same lengths. Accordingly, means are provided for moving the blanks axially in the same direction and to the same point regardless of whether screws 11 are up or down. This is preferably 50 accomplished by enlarging the last few threads 42 at the delivery ends of the fixed screws 1 and making them shallow so that they will lift the blanks out of engagement with screws 11 even when the latter are in their upper operative position. The adjacent threads 43 of screws 11 are reduced in diameter to make room for the enlarged threads of screws 1. As blanks at the delivery ends of the screws can be engaged only by enlarged shallow threads 42, they can move in 55 only one axial direction, to the right in Figs. 1 and 2. To assure all of the blanks leaving the straightening machine at the same point longitudinally thereof, a stop is provided against which their forward ends abut before rolling off the ends 60 of screws 1. As shown in Figs. 1 and 3, this stop may be formed conveniently by enlarging one of the upright members 37 so that it will extend across the path of the axially moving screws.

In the embodiment of the invention illustrated 70 diagrammatically by Fig. 5, a plurality of screw flights 51 are disposed in alternating relation with a plurality of screws 52. The screws of one group have their flights wound in one direction, while those of the other wind in the opposite direction. 75

but all screws are rotated in the same direction of flight travel. Contrary to the first embodiment of the invention, all of these screws are mounted in fixed bearings with the axes 53 of screws 51 on the same level as the axes 54 of screws 52. However, although the periphery of each flight 51 is concentric with its axis 53, the periphery of each flight 52 is eccentric relative to its axis 54. Consequently, the tops of screws 52 are below the tops of screws 51 part of the time, during which time a blank 59 is engaged only by screws 51, and above the tops of screws 51 the rest of the time. As the blank-engaging portions of the eccentric screws rise above like portions of screws 51, they lift the blank therefrom as shown in broken lines. The blank therefore periodically travels axially in opposite directions as it is carried lengthwise of the screws. This form of the invention has the advantage of no lifting frame and lifting mechanism, but is not as satisfactory when the amount of axial movement of the blank that can take place between the rising and falling of the eccentric screws is insufficient to expose all of the blank directly to the action of the screws.

According to the provisions of the Patent Statutes, I have explained the principle and mode of operation of my invention and have illustrated and described what I now consider to represent its best embodiment. However, I desire to have it understood that, within the scope of the appended claims, the invention may be practiced otherwise than as specifically illustrated and described.

I claim:

1. A machine for straightening cylindrical blanks, comprising parallel rotatably mounted right and left-hand screw flights disposed in two groups with all flights of like hand in a single group, said flights being formed to receive a blank transversely thereof and to engage it on opposite sides at longitudinally spaced points, means for rotating said screws to rotate and straighten the blank while conveying it longitudinally of the screws, and means for periodically effecting vertical movement of said groups of screws relative to each other whereby said blank is operatively engaged by only one group at a time to cause it to travel axially alternately in opposite directions.

2. A machine for straightening cylindrical blanks, comprising a group of parallel rotatably mounted right-hand screw flights, a group of parallel rotatably mounted left-hand screw flights at least some of which are disposed between some of the right-hand screws, said flights being formed to receive a blank transversely thereof and to engage it on opposite sides at longitudinally spaced points, means for rotating said screws to rotate and straighten the blank as it is conveyed longitudinally of the screws, and means for periodically raising and lowering at least one of said groups of screws to move their axes above and below the axes of the screws in the other group, whereby said blank is operatively engaged by only one group of screws at a time to cause it to travel axially alternately in opposite directions.

3. A machine for straightening cylindrical blanks, comprising a plurality of parallel rotatably mounted alternately arranged right and left-hand screw flights, the flights of each screw being formed to receive a blank transversely thereof and to engage it substantially on its diametrically opposite sides at longitudinally spaced points, means for rotating all of said screws in a common

direction of flight travel to rotate and straighten the blank while conveying it longitudinally of the screws, and means for periodically raising and lowering one of the groups of screws of like flight to move their axes above and below the axes of the screws in the other group, whereby said blank is operatively engaged by only one group of screws at a time to cause it to travel axially alternately in opposite directions.

4. A machine for straightening cylindrical blanks, comprising parallel rotatably mounted right and left-hand screw flights disposed in two groups with all flights of like hand in a single group, said flights being formed to receive a blank transversely thereof and to engage it on opposite sides at longitudinally spaced points, means for rotating said screws to rotate and straighten the blank while conveying it longitudinally of the screws, and means for periodically effecting vertical movement of said groups of screws relative to each other whereby said blank is operatively engaged by only one group at a time to cause it to travel axially alternately in opposite directions, the flights at the delivery ends of the screws of one group being shallow for raising the blank out of engagement with the other group of screws and conveying it axially.

5. A machine for straightening cylindrical blanks, comprising parallel rotatably mounted right and left-hand screw flights disposed in two groups with all flights of like hand in a single group, said flights being formed to receive a blank transversely thereof and to engage it on opposite sides at longitudinally spaced points, means for rotating said screws to rotate and straighten the blank while conveying it longitudinally of the screws, and means for periodically effecting vertical movement of said groups of screws relative to each other whereby said blank is operatively engaged by only one group at a time to cause it to travel axially alternately in opposite directions, the flights at the delivery ends of the screws of one group being enlarged and shallow relative to the remaining flights for lifting the blank out of engagement with the other group of screws and conveying it axially.

6. A machine for straightening cylindrical blanks, comprising parallel rotatably mounted right and left-hand screw flights disposed in two groups with all flights of like hand in a single group, said flights being formed to receive a blank transversely thereof and to engage it on opposite sides at longitudinally spaced points, means for rotating said screws to rotate and straighten the blank while conveying it longitudinally of the screws, means for periodically effecting vertical movement of said groups of screws relative to each other whereby said blank is operatively engaged by only one group at a time to cause it to travel axially alternately in opposite directions, the flights at the delivery ends of the screws of one group being shallow for raising the blank out of engagement with the other group of screws and conveying it axially, and a stop member at one end of the machine for arresting said last-mentioned axial movement of the blank.

7. A machine for straightening cylindrical blanks, comprising a plurality of parallel rotatably mounted alternately arranged right and left-hand screw flights, the flights of each screw being formed to receive a blank transversely thereof and to engage it on opposite sides at longitudinally spaced points, means for rotating all of said screws in a common direction of flight travel to rotate and straighten the blank while

- conveying it longitudinally of the screws, means for mounting one group of screws of like flight in fixed position, and means for periodically raising and lowering the other group of screws to periodically lift the blank from the first group of screws, whereby the blank is operatively engaged by only one group at a time to cause it to travel axially alternately in opposite directions.
10. A machine for straightening cylindrical blanks, comprising a plurality of parallel rotatably mounted alternately arranged right and left-hand screw flights, the flights of each screw being formed to receive a blank transversely thereof and to engage it on opposite sides at longitudinally spaced points, means for rotating all of said screws in a common direction of flight travel to rotate and straighten the blank while conveying it longitudinally of the screws, means
15. for mounting one group of screws of like flight in fixed position, and means for periodically raising and lowering the other group of screws to periodically lift the blank from the first group of screws, whereby the blank is operatively engaged by only one group at a time to cause it to travel axially alternately in opposite directions, the flights at the delivery ends of the screws of the fixed group being enlarged and shallow for raising the blank out of engagement with the movable group of screws and conveying it axially.
20. A machine for straightening cylindrical blanks, comprising a plurality of parallel rotatably mounted alternately arranged right and left-hand screw flights, the flights of each screw being formed to receive a blank transversely thereof and to engage it on opposite sides at longitudinally spaced points, means for rotating all of said screws in a common direction of flight travel to rotate and straighten the blank while conveying it longitudinally of the screws, means
25. for mounting one group of screws of like flight in fixed position, and means for periodically raising and lowering the other group of screws to periodically lift the blank from the first group of screws, whereby the blank is operatively engaged by only one group at a time to cause it to travel axially alternately in opposite directions, the flights at the delivery ends of the screws of the fixed group being enlarged and shallow for raising the blank out of engagement with the movable group of screws and conveying it axially.
30. A machine for straightening cylindrical blanks, comprising a plurality of parallel rotatably mounted alternately arranged right and left-hand screw flights, the flights of each screw being formed to receive a blank transversely thereof and to engage it on opposite sides at longitudinally spaced points, means for rotating all of said screws in a common direction of flight travel to rotate and straighten the blank while conveying it longitudinally of the screws, means
35. for mounting one group of screws of like flight in fixed position, and means for periodically raising and lowering the other group of screws to periodically lift the blank from the first group of screws, whereby the blank is operatively engaged by only one group at a time to cause it to travel axially alternately in opposite directions, the flights at the delivery ends of the screws of the fixed group being enlarged and shallow for raising the blank out of engagement with the movable group of screws and conveying it axially.
40. A machine for straightening cylindrical blanks, comprising a plurality of parallel rotatably mounted alternately arranged right and left-hand screw flights, the flights of each screw being formed to receive a blank transversely thereof and to engage it on opposite sides at longitudinally spaced points, means for rotating all of said screws in a common direction of flight travel to rotate and straighten the blank while conveying it longitudinally of the screws, means
45. for mounting one group of screws of like flight in fixed position, and means for periodically raising and lowering the other group of screws to periodically lift the blank from the first group of screws, whereby the blank is operatively engaged by only one group at a time to cause it to travel axially alternately in opposite directions, the flights at the delivery ends of the screws of the fixed group being enlarged and shallow for raising the blank out of engagement with the movable group of screws and conveying it axially, the adjacent flights at the delivery ends of the screws of the vertically movable group being reduced in diameter.
50. A machine for straightening cylindrical blanks, comprising parallel rotatably mounted right and left-hand screw flights disposed in two groups with all flights of like hand in a single group, said flights being formed to receive a blank transversely thereof and to engage it on opposite sides at longitudinally spaced points, means for rotating said screws to rotate and straighten the blank while conveying it longitudinally of the screws, means for periodically effecting vertical movement of said groups of screws relative to each other whereby said blank is operatively engaged by only one group at a time to cause it to travel axially alternately in opposite directions,
55. and means disposed at the ends of the machine and actuated by engagement of the blank therewith for periodically reversing said vertical movement effecting means.
60. A machine for straightening cylindrical blanks, comprising a plurality of parallel rotatably mounted alternately arranged right- and left-hand screw flights, the flights of each screw being formed to receive a blank transversely thereof and to engage it substantially on its diametrically opposite sides at longitudinally spaced points, means for rotating all of said screws in a common direction of flight travel to rotate and straighten the blank while conveying it longitudinally of the screws, means for periodically raising and lowering one of the groups of screws of like flight to move their axes above and below the axes of the screws in the other group, whereby said blank is operatively engaged by only one group of screws at a time to cause it to travel axially alternately in opposite directions, and means disposed at the ends of the machine and actuated by engagement of the blank therewith for periodically reversing said raising and lowering means.
65. 12. A machine for straightening cylindrical blanks, comprising a plurality of parallel rotatably mounted alternately arranged right and left-hand screw flights, the flights of each screw being formed to receive a blank transversely thereof and to engage it substantially on its diametrically opposite sides at longitudinally spaced points, means for rotating all of said screws in a common direction of flight travel to rotate and straighten the blank while conveying it longitudinally of the screws, means for periodically raising and lowering one of the groups of screws of like flight to move their axes above and below the axes of the screws in the other group, whereby said blank is operatively engaged by only one group of screws at a time to cause it to travel axially alternately in opposite directions, and means disposed at the ends of the machine and actuated by engagement of the blank therewith for periodically reversing said raising and lowering means.
70. 13. A machine for straightening cylindrical blanks, comprising a stationary frame, a plurality of spaced parallel screw flights rotatably mounted at their ends on said frame, a vertically movable frame mounted below said screws, a plurality of spaced parallel screw flights rotatably mounted at their ends on said movable frame between the screws of the first-mentioned group, the flights of one group being right-hand and those of the other group being left-hand and all being formed to receive a blank transversely thereof and to engage it on opposite sides at longitudinally spaced points, means for rotating all of said screws in a common direction of flight travel to rotate and straighten the blank while conveying it longitudinally of the screws, and means for periodically raising and lowering said movable frame to cause the screws mounted thereon to periodically lift the blank from the other group of screws and return it thereto, whereby the blank is operatively engaged by only one group of screws at a time and thereby caused to alternately travel axially in opposite directions.
75. 14. A machine for straightening cylindrical blanks, comprising parallel rotatably mounted right and left-hand screw flights disposed in two groups with all flights of like hand in a single group, said flights being formed to receive a blank transversely thereof and to engage it on opposite sides at longitudinally spaced points, and means for rotating said screws to rotate and straighten the blank while conveying it longitudinally of the screws, the flights of one of said

groups being eccentric relative to their axes whereby they periodically engage the blank and lift it from the other screws.

15. A machine for straightening cylindrical blanks, comprising parallel rotatably mounted right and left-hand screw flights disposed in two groups with all flights of like hand in a single group, said flights being formed to receive a blank transversely thereof and to engage it on opposite sides at longitudinally spaced points, means for rotating said screws to rotate and straighten the blank while conveying it longitudinally of the screws, and periodically rising rotating means for lifting the blank 5 from said flights and reversing its direction of axial movement.

16. A machine for straightening cylindrical blanks, comprising a plurality of parallel screw flights wound in the same direction, said flights 10 being formed to receive a blank transversely thereof and to engage it on opposite sides at longitudinally spaced points, means for rotating said screws to rotate and straighten the blank while conveying it longitudinally of the screws, and periodically 15 effecting vertical movement of said groups of screws relative to each other whereby said blank is operatively engaged by only one group at a time to cause it to travel axially alternately in opposite directions, and means at the delivery ends of the screws of one group for raising the 20 blank out of engagement with the other group of screws and conveying it axially.

16. A machine for straightening cylindrical blanks, comprising a plurality of parallel screw flights wound in the same direction, said flights 25 being formed to receive a blank transversely

thereof and to engage it on opposite sides at longitudinally spaced points, means for rotating said screws to rotate and straighten the blank while conveying it longitudinally of the screws, and periodically rising rotating means for lifting the blank 5 from said flights and reversing its direction of axial movement.

17. A machine for straightening cylindrical blanks, comprising a plurality of parallel screw flights wound in the same direction, said flights 10 being formed to receive a blank transversely thereof and to engage it on opposite sides at longitudinally spaced points, means for rotating said screws to rotate and straighten the blank while conveying it longitudinally of the screws, 15 and periodically rising rotating screw flights for lifting the blank from the first-mentioned flights, said rising flights being wound in the direction opposite to said first-mentioned flights, and means for rotating said rising flights in the direction opposite to the direction of rotation of the first-mentioned screws, whereby the blank 20 travels axially alternately in opposite directions.

BENJAMIN P. HAZELTINE. 25
